RECONDITIONING OLD BOOKS AND
LEDGERS

Maynard R. Hultman, Pittsburgh, Pa.

Application March 14, 1936, Serial No. 68,953

1 Claim. (Cl. 281—21)

This invention relates to the reconditioning of old books and ledgers, particularly public records such as deed books and the like which are consulted constantly and as a result of frequent folding break near the back. These heavy books must be rebound when such signs of wear appear so that they may again be handled through a long period of time.

It is customary to trim the old pages and attach new binding strips to the trimmed edges for renewing the folded edges of these books. Such binding strips when bound together by sewing or binder posts or rings add new material in the binding edge of the book thereby strengthening the volume so that each page will fold or bend in the new strip and thus relieve the frail old pages of strain.

In a heavy public record such as a deed book the pages are not only subjected to folding strain in the binding but also to an additional shearing stress produced by a tendency of the page to be forcibly swiveled as the reader grasps the page at the corner to open it or to turn it. As a result of this torsional strain paper binding strips deteriorate in a much shorter time than should be expected. Cloth binding strips due to their limpness will withstand about five times the abuse paper binding strips will withstand, but cloth is expensive and in practice has been found to take longer to apply than paper.

Therefore, it is an object of this invention to increase the life and reduce the expense and time required to recondition old volumes, and to this end the invention employs paper binding strips for the last pages of the book and cloth binding strips for the first thirty to fifty pages for these pages are opened wider and receive more abuse than the rest of the pages.

It is highly desirable that the reconditioned volume have no greater thickness than the original volume. If all of the binding strips are of the same width increased thickness results at the junctures between the book pages and the cloth or paper binding strips. Where all of the pages are skived the reconditioned volume will have requisite thinness but skiving is time consuming. Sometimes a long page alternating with a short page, without any skiving, is used, but here again the thickness of the volume is increased to an undesirable extent.

A further object of my invention is therefore to provide a method of reconditioning old ledgers, books and volumes, whereby the thickness of the book is not increased by the addition of the binding strips, and a stronger and longer lived bind-

ing will be produced, both of these advantages being attained at reduced cost and at minimum expenditure of time to recondition an old book. To attain these ends the invention contemplates the use of alternate long and short pages, one of which is skived, and binding strips of different widths corresponding to the length of their associated pages.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a plan view of a book page equipped with a fabric binding strip in accordance with the invention and showing the binding strip prior to folding.

Figure 2 is an edge view of the page and binding strip shown in Figure 1, drawn to enlarged scale.

Figure 3 is a plan view of a book page shorter than the page shown in Figure 1 and having a skived rear edge to which is secured a fabric binding strip of greater width than the binding strip shown in Figure 1.

Figure 4 is an edge view of the page and binding strip shown in Figure 3, drawn to enlarged scale.

Figure 5 is an enlarged detail cross sectional view showing alternate long and short pages, such as illustrated in the previous figures, assembled with their binding strips folded, and showing several pages having fabric binding strips and the remainder having paper binding strips in accordance with the invention.

Referring now to the drawing in which like characters of reference designate similar parts in the various views, 10 indicates a page of a book to be reconditioned. The back or rear edge of the page is trimmed off evenly and a fabric binding strip 11 is lapped at one longitudinal edge on the page and pasted securely thereto at the lap. The binding strip is adapted to be folded longitudinally upon itself as indicated by the scored line 12. The fabric may be muslin, linen, gingham, percale, or other limp fibrous material which has the capacity to not only resist folding indefinitely, but also to stand up indefinitely under torsional strains such as the pages of a book are subjected to.

In Figure 3 there is shown a page 13 of the book to be reconditioned, this page preferably being the next page in numerical order to the page shown in Figure 1. The page 13 is 5 trimmed at the back edge to be shorter in length than the page 10 and is skived at the back edge as shown at 14 in Figure 4. A fabric binding strip 15 preferably of the same material as the binding strip 11 but not necessarily so, is pasted at 10 one longitudinal edge to the skived edge of the page 13. The fabric binding strip 15 is of greater width than the fabric binding strip 11 and is folded upon itself along the scored line 16. The 15 scored lines 12 and 16 coincide when the pages are stacked preparatory to binding by sewing or otherwise, as best shown in Figure 5. By virtue of the page 13 being shorter than the page 10, the back edge of the page will not underlie the back edge of the page 10 but will be spaced considerably forwardly of the latter.

The fabric strip of the page 10 may be folded back until its free longitudinal edge 17 approximately abuts the rear edge of the page 10. The fabric strip 15 of the page 13 is folded back upon 25 itself so that its longitudinal edge 18 approximately abuts the rear edge of the next underlying long page 10, as best shown in Figure 5.

It will be pointed out that in practice about a quarter of an inch space exists between the skived 30 edge of a short page 13 and the rear edge of a long page 10 and this space accommodates an accumulation of the fabric strip as shown also in Figure 5.

In further carrying out the invention the first 35 thirty five to fifty pages of the book are provided with fabric binding strips constructed as above described. The following pages to the end of the book are provided with paper binding strips constructed identically and applied identically as 40 above described. No numerals have been given to the paper binding strips in Figure 5, the difference in cross hatching the fabric and paper being relied upon to differentiate one structure from the other.

45 The purpose of equipping the first pages of the book with fabric binding strips is to increase the life of the reconditioned book since fabric due

to its limpness will withstand about five times the abuse that the paper binding strips will withstand and hence fabric binding strips are employed for the initial pages of the book for these 5 pages are opened wider and receive more abuse than the rest of the pages.

By virtue of the junctures of alternate long and short pages with their associated binding strips, being disposed out of alignment with each other and one of the pages being skived, the 10 thickness of the reconditioned book at the junctures of the binding strips with the pages will not be increased, assuming of course that the thickness of the binding strip, whether fabric or paper, 15 is about one half the thickness of the book page.

By skiving only one half the pages the time consumed in reconditioning a book is materially shortened. By using a number of fabric binding strips for the pages subjected to the most abuse the long life of the book will be greatly promoted 20 over books bound with paper binding strips only.

Finally an old book reconstructed as above described may be handled freely without appreciable deterioration for longer periods of time and under more severe conditions of service than 25 hitherto possible.

From the above description it is thought that the construction and operation of the invention will be fully understood without further explanation.

30 What is claimed is:

A reconditioned book having alternate long and short pages, the rear edges of the long pages being trimmed, the rear edges of the short pages being skived, binding strips of one-half the thickness 35 of the pages secured to the trimmed rear edges of the pages by overlapping, and binding strips of one-half the thickness of the pages secured to the skived rear edges of the pages, the overlapped and skived seams being arranged in staggered relation, all of the binding strips being folded back upon themselves, the bights of the folds being in 40 alignment, all of the binding strips having their free edges disposed in close proximity to the trimmed rear edges of the pages.
